UNITED STATES PATENT OFFICE

2,487,930

FURNACE ROOF AND REMOVABLE GAUGE
PIN FOR DETERMINING THE CONDITION
THEREOF

Howard Y. Lankford, Gary, Ind., assignor to Carnegie-Illinois Steel Corporation, a corporation of New Jersey

Original application October 21, 1946, Serial No. 704,645, now Patent No. 2,470,498, dated May 17, 1949. Divided and this application April 20, 1948, Serial No. 22,164

6 Claims. (Cl. 110—99)

1

This invention relates to furnace roofs and more particularly to a roof for an open-hearth furnace and a removable gauge pin for determining when it requires replacement.

This is a division of my application Serial No. 704,645, filed October 21, 1946, which has matured into Patent No. 2,470,498, dated May 17, 1949, for "Furnace roof and accessories therefor."

The roofs of open-hearth furnaces such as used in making steel are subjected to extremely severe working conditions and must be reconstructed periodically. This necessitates shutting down the furnace with a consequent loss of production. Hot spots in the roof are a common cause of failure since they result in accelerated localized deterioration by erosion. They are caused by improper flame distribution which cannot always be avoided. Non-uniform temperature conditions over the area of the roof cause destructive variations of compressive stress in the brick composing the roof arch, by reason of differential expansion and contraction. Hot spots in the roof, furthermore, cause temperature differences in the bath since the latter is heated by radiation from the flame and roof, and this condition impairs the quality of the product.

It is impossible to determine the remaining life of a roof or the existence or location of hot spots by visual inspection of the lower surface thereof. Even if it were, the necessity of opening the charging doors for a time long enough to permit the inspection would be undesirable because of the induction of excess air, loss of heat and the danger of creating further temperature differences between various points in the bath or over the surface of the roof. If it were possible to detect hot spots in the roof, the danger of accelerated deterioration could be reduced by shifting the direction of the flame somewhat.

Heretofore, it has been assumed that a roof is good for so many heats, say 200, and that after that number has been reached, rebuilding is necessary. While hot spots in the furnace roof generally indicate localized erosion to a dangerous thinness, it has frequently been discovered, after the brickwork has been torn down, that the roof actually was in better condition than anticipated and would have rendered good service for an additional number of heats. On the other hand, the brickwork of the roof is sometimes weaker than would appear, even though no hot spots occur, with the end result that the roof caves in.

It is the principal object of my invention, therefore, to provide a furnace roof with means which will make possible a quick and easy determination

2

of the thickness of the bricks of which the roof is composed, at various critical locations, from time to time during the life of the roof while the furnace is in operation, and thus permit an accurate estimate of the remaining life of the roof.

Another object is to provide a roof construction permitting the taking of temperature readings, either "spot" or "continuous," at desired critical locations and elevations without cutting into or weakening the roof structure, and without necessitating the opening of the charging doors of the furnace.

Still another object is to provide a construction which permits the ready checking of the velocity of the flame within the furnace, with the result that the direction and range thereof may be accurately controlled.

A further object is the attainment of the foregoing results at a low installation and maintenance cost.

In a preferred embodiment of the invention, I provide apertures in the brick arch forming the furnace roof, above certain critical points distributed over the area of the hearth. To this end, I lay a special brick in the roof above such points, having a tapered bore therethrough. I place a tapered sleeve or liner in the bore of each such brick and fit a tapered removable plug or pin in each sleeve. The brick, sleeve and pin are composed of refractory material similar to that of which the other roof bricks are made. They deteriorate by erosion and the like, therefore, at about the same rate as the other bricks in the vicinity. The progress of such erosion may thus be readily observed from time to time by taking out the pins and observing their reduction in length. The apertures also permit temperature measurements to be made and the velocity of combustion gases to be observed.

A complete understanding of the invention may be obtained from the following detailed description and explanation when read in conjunction with the accompanying drawings illustrating the present preferred embodiment. In the drawings,

Figure 1 is a partial horizontal section through one end of an open-hearth furnace indicating by intersecting center lines the location of apertures in the roof of the furnace for the purposes of the present invention;

Figure 2 is a partial vertical longitudinal section taken on line II—II of Figure 1;

Figure 3 is a transverse section taken on line III—III of Figure 1;

Figure 4 is an axial section through one of the special bricks showing the sleeve and pin therein;

Figure 5 is an elevation of the tapered pin which forms part of the assembly of Figure 4; and

Figure 6 is an elevation partly in section showing the tapered liner or sleeve which also forms part of the assembly of Figure 4.

Referring more particularly to the drawings, the furnace there shown comprises a hearth 1 with side walls and a roof 2 thereover. As shown most clearly in Figure 3, the roof 2 is an arch composed for the most part of refractory brick-work. At a plurality of spaced locations, a special brick is laid in the roof arch. This brick is preferably prismatic in shape, is laid with its greatest dimension radial and extends the full thickness of the roof. Each of these special bricks is composed of a pair of vertically opposed refractory brick halves 3 which, when assembled, provide a rectangularly shaped brick with a longitudinally extending frusto-conical bore 4. That is to say, each of the brick halves 3 is defined by exterior surfaces which extend at 90° with respect to the adjacent and connecting surfaces except for one longitudinally extending face which is recessed to conform to one-half of a frustum of a cone. When installed in the roof of the furnace, a pair of brick halves 3 are so assembled that the largest diametral portion of the frusto-conical bore 4 is at the upper surface of the roof 2.

Within the frusto-conical bore 4 provided by each assembled pair of brick halves 3 I fit a conformingly shaped tubular liner or sleeve 6, which also has a frusto-conical bore. The desired shape of the liner is preferably achieved by making its wall of substantially uniform thickness, whereby the largest diametral portions of both the exterior and the bore thereof are at the same end of the liner. The length of the liner is substantially the same as that of the sectional refractory brick within which it is disposed.

Referring to Figures 4 and 5 of the drawings, the invention also comprises a refractory pin or plug 8 having a main body portion, or shank, which conforms in size and shape to the frusto-conical bore of the tubular refractory liner 6. At the larger end of the main body portion or shank of the pin 8 is formed an integral flange or collar 10 surmounted by an integral frusto-conical head 12. The head 12 has a transverse hole 13 through which a rod, hook or other pulling means (not shown) may be inserted in order to facilitate the removal of the pin.

The brick may be of silica like the other roof bricks. The sleeve 6 and pin 8 are preferably composed of sillimanite. This refractory material is generally similar in characteristics to that of which the other roof bricks are composed but exhibits less tendency to fuse and cause sticking. The sleeve and pin as well as brick 3 are eroded by the combustion gases in the furnace, therefore, at about the same rate and to about the same extent as the other bricks in their immediate vicinity.

During operation of the furnace, the apertures in the roof afforded by the bricks 3 and liners 6 remain closed by the pins 8 inserted therein. After a period of operation, the extent of roof erosion may be gauged by inspection of the pins. Upon removal of any one of the pins 8, the length of the portion of the shank remaining reveals how much erosion has taken place in the neighborhood thereof. For this purpose, the original height of the liners 6, brick elements 3 and the length of the shanks of the pins 8 are

made equal to the thickness of the brick of which the furnace roof is composed. The length of the shank remaining at any time thus shows the progress of erosion of the inner surface of the roof at that particular point. In addition, various measuring accessories or instrumentalities may be inserted through the apertures in the roof thus provided for the purpose of making determinations regarding temperature, direction and velocity of flame or the like.

In an open-hearth furnace of conventional shape and size, three apertures spaced along each of five center lines transverse to the furnace axis as shown in Figure 1, should ordinarily be sufficient to make possible accurate determination of the condition of the furnace roof at any given point. More specifically, one center line should traverse each knuckle 14, another the tapping hole of the furnace, and another the point half-way between the tapping hole and each knuckle. It is to be understood, however, that the number and location of the test apertures may be other than those mentioned, as may be determined empirically. The test apertures are made accessible from the top of the furnace by providing ladders above the tie rods connecting the buck-stays on opposite sides of the furnace.

While I have shown and described a specific embodiment of my invention, it will be understood that changes therein may be made without departing from the spirit of the invention or the scope of the appended claims.

I claim:

1. In a furnace roof, a brick arch, a number of 35 bricks laid therein in spaced relation over the area thereof having a bore therethrough, and a pin fitting snugly but removably therein, said bricks and pins being composed of refractory material similar to that of the other bricks in the arch, 40 whereby the length of one of the pins at any time affords a measure of the erosion of the roof in the immediate vicinity.

2. The construction defined by claim 1 characterized by said bore and pin tapering inwardly 45 to substantially the same degree.

3. The construction defined by claim 1 characterized by a refractory liner in said bore having a substantially uniform wall thickness.

4. The construction defined by claim 1 characterized by each of said pins having a head engaging the outer end of the brick in which it fits.

5. The construction defined by claim 1 characterized by said pins extending substantially the 55 full length of said bores.

6. In a furnace roof composed of a brick arch, the improvement comprising a brick laid in said arch having a radial bore therethrough and a pin fitting snugly but removably in said bore, said 60 brick and pin being composed of refractory material similar to that of the other bricks in the arch.

HOWARD Y. LANKFORD.
